Inventor:

By Drake & Co. Atty's.

UNITED STATES PATENT OFFICE.

WILLIAM H. JAMOUNEAU, OF NEWARK, NEW JERSEY.

DESIGN FOR A SPOON, &c.

SPECIFICATION forming part of Design No. 21,252, dated December 22, 1891.

Application filed June 11, 1891. Serial No. 395,968. Term of patent 7 years.

To all whom it may concern:

Be it known that I, WILLIAM H. JAMOUNEAU, a citizen of the United States, residing at Newark, in the county of Essex and State of New Jersey, have invented and produced a new and original Design for Handles for Spoons, Forks, &c.; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

15 The figure of the drawing is a front plan of a spoon having a handle of my new design, of which the following is a specification, the one figure being deemed sufficient to fully illustrate the same.

20 The leading feature of the design consists in the handle for spoons, forks, and such like articles, with the phenix-shaped extremity, with flame-shaped ornamentation beneath or below the phenix representation, as will now be described.

25 In the said drawing, *a* indicates the bowl of a spoon, *b* the narrow or shank-shaped part

thereof, and *c* is the wider flange-like part. At the extremity of the said wider part the same is shaped in resemblance to a phenix, 30 as at *d*, with wings uplifted in a conventional style. Between the uplifted wings is a disk-like ornament *f*, shaped in resemblance to the sun as it rises above waves or clouds *g*, and from said disk-like ornament are rays *h*, extending outwardly toward the border of the handle. Beneath the phenix-shaped part, toward the narrower part of the handle, is ornamentation in resemblance to flame, from which the phenix appears to rise. 40

What I claim as new is—

The design for a handle for a spoon, &c., herein described, which consists in the handle having a narrow shank-shaped part *b*, and a wider part *c*, ornamented in resemblance to a conventional phenix rising from flames, substantially as shown and described. 45

In testimony that I claim the foregoing I have hereunto set my hand this 26th day of May, 1891.

WM. H. JAMOUNEAU.
